Primary Examiner—Bernard Ansher*Assistant Examiner*—Prabhakar Deshmukh*Attorney, Agent, or Firm*—Eckert, Seamans, Cherin & Mellott[57] **CLAIM**

The ornamental design for a baseball game counter, as shown and described.

DESCRIPTION

FIG. 1 is a perspective view of a baseball game counter showing my new design;

FIG. 2 is a bottom plan view thereof;

FIG. 3 is a left side elevational view thereof;

FIG. 4 is a right side elevational view thereof; and,

FIG. 5 is a rear elevational view thereof.

The broken line showing of a wriststrap is for illustrative purposes only and forms no part of the claimed design.

Fig. 1.

Fig. 2.

Fig. 3.

Fig. 5.
